UNITED STATES PATENT OFFICE.

LOUIS C. F. FREES, OF NEW YORK, N. Y.

NECKTIE.

SPECIFICATION forming part of Letters Patent No. 269,658, dated December 26, 1882.

Application filed May 17, 1882. (No model.)

To all whom it may concern:

Be it known that I, LOUIS C. F. FREES, of New York, in the county of New York and State of New York, have invented certain new and useful Improvements in Neckties; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of one of my improved neckties or bows, showing in dotted lines several different positions of the hook which forms the subject-matter of my invention; and Fig. 2 is a detail view of the hook detached from the bow.

Like letters of reference indicate corresponding parts in both the figures.

My invention has relation to that particular class of men's neckwear known in the trade as "band-bows," intended to be worn with standing collars; and it consists in providing the "bow" with a permanent wire hook of peculiar construction, which forms part of the article, and is adapted to catch under the lower rim of the front part of the standing collar, so as to prevent the neckwear from working up over the collar, substantially as hereinafter more fully described and claimed.

In the accompanying drawings, the letter A designates the bow, and B the "band," which passes around the standing collar, and after being passed through the loop b of the bow is fastened in the bow (on the inside) by a pin, C. The hook or catch is shown at D D', from which it will be seen that it consists of a piece

of wire doubled upon itself, and then bent or shaped to form parallel straight arms D' and D, connected by the lower part, d, the free ends of the wire being spread apart and bent to form the loops or eyes a a. The part D' is inserted from the inside through a slit, e, in the loop-band B', so that the part D will project into the loop covered by the band B', in which position it is prevented from turning sidewise by the eyes or enlargements a a. By slipping the upwardly-projecting catch D' under the collar between the neckband of the shirt and the front part of the collar, it will be seen that said part D' will effectually prevent the bow from working up upon the collar, so that the bow and band will always maintain their proper relative position to this.

I am aware that so-called "necktie-fastenings" have been constructed before in which a wire yoke clasps the collar-button, as shown in the patent to P. S. White, No. 97,331, of November 30, 1869; but I do not claim the construction of a clasp or fastening as therein shown.

What I claim, and desire to secure by Letters Patent of the United States, is—

The improved band-bow composed of the neckband B, bow A, loop-band B', slitted at e, pin C, and collar-catch D D', constructed and combined substantially as and for the purpose herein shown and set forth.

In testimony that I claim the foregoing as my own I have hereunto affixed my signature in presence of two witnesses.

LOUIS CHARLES FREDERIK FREES.
